United States Patent Office

Des. 185,235
Patented May 19, 1959

185,235

WHISTLE

Adorno Raffaelli, Reading, Pa.

Application October 30, 1958, Serial No. 53,213

Term of patent 7 years

(Cl. D56—1)

Figure 1 is a front perspective view of a whistle showing my new design;

Figure 2 is a bottom plan view thereof;

Figure 3 is a sectional view thereof on line 3—3 of Figure 1; and

Figure 4 is a fragmentary rear perspective view thereof.

I claim:

The ornamental design for a whistle, as shown.
